UNITED STATES PATENT OFFICE.

ARNOLD MOETTELI, OF OBERWINTERTHUR, SWITZERLAND.

CONTAINER FOR THE DRY COOLING OF COKE.

Application filed February 1, 1923. Serial No. 616,298.

To all whom it may concern:

Be it known that I, ARNOLD MOETTELI, a citizen of Switzerland, residing at Oberwinterthur, Switzerland, Alte Romerstrasse 21, have invented certain new and useful Improvements in Containers for the Dry Cooling of Coke, of which the following is a specification.

The present invention relates to a container for the dry-cooling of incandescent coke in which the coke is cooled by means of a gaseous medium delivered at the lower end of the container from an enclosed space; according to this invention the bottom of the container is formed conically on one side and terminates in a conveyor belt forming a discharging arrangement, by means of which the coke can be removed from the container without the delivery of the cooling 20 gases being interrupted.

One example of carrying out the subject of the invention is shown in the drawing.

a is the container in which the coke is cooled, *c* is the bottom thereof consisting 25 of two hoppers arranged co-axially one over the other, the lower being formed conically on one side; from the annular space *c* between the hoppers cooling gases are delivered through the coke from the bottom to the top.

30 For discharging the container a conveyor belt *r* running on the wheels *p* and the rollers *q* is provided at the mouth of the lower hopper and is driven in the direction of the arrows by one of the wheels *p*.

When the belt is set in motion, the coke on it, which is continually being supplied a fresh from the container, is conducted through the side opening *s* of the hopper onto the shoot *t* and thence delivered to a truck placed ready below. In order to effect the hermetic sealing of the container the conveyor belt is enclosed by a casing *u* which on the shoot side is opened by means of the trap door *v* during the discharging period.

By means of the arrangement here described it is rendered possible to regulate the speed of discharging the coke container at will, at the same time avoiding absolutely any disturbance of the cooling process.

I claim:

A device for dry cooling coke comprising a container with a conical bottom, an enclosed space below said container, means for introducing cooling gases through said enclosed space into the container; a conveyor belt below the conical bottom and within the enclosed space for discharging the coke, whereby the coke is discharged without interrupting the flow of cooling gases.

In testimony whereof I have affixed my 60 signature in presence of two witnesses.

ARNOLD MOETTELI.
